UNITED STATES PATENT OFFICE.

LEOPOLD SCHULL, OF VIENNA, AUSTRIA.

DRIVING MECHANISM FOR PRESSES.

Application filed July 13, 1925, Serial No. 43,426, and in Austria March 14, 1924.

This invention relates to improvements in eccentric presses, namely, in presses of the type in which the ram is actuated by an eccentric mounted on the shaft of the press.

During the working stroke of the eccentric, which causes the ram to move downwardly, for example, the standard of the press is subjected to tension. Upon the upward movement of the ram the reaction of the tensed or extended standard imparts to the shaft of the press the potential energy stored therein so that the reaction of the standard then tends to actuate the shaft and the flywheel mounted thereon. This is accomplished by means of the ram which is connected to the eccentric rod, and the eccentric which is directly mounted on the shaft. The impulse which is thus imparted to the shaft of the press by means of the reaction of the standard injuriously affects the coupling members which connect the said shaft to a primary driving member. These coupling members ordinarily have bolts, lugs or the like or one of them, which enter into slots located in the other member of the coupling, and these slots permit a relative lateral play or movement therein of the entering parts. In order to obviate these disadvantages, couplings have been proposed in which the play of the entering bolts or the like has been obviated. However, owing to the considerable pressure exerted by the entering driving members upon the walls of the slots, such devices have not been a success, more particularly because of the numerous and sudden changes in driving force incidental to the operation of fast running presses.

According to the present invention, which is very well adapted for eccentric presses provided with couplings of any desired construction and adapted to be thrown-in during the operation, the disadvantages just described are obviated by means of arranging an additional friction-coupling, which is effective in case of a relative rotation of the two parts to be coupled, opposite in direction to the desired revolution thereof.

One embodiment of the present invention is illustrated by way of example on the accompanying sheet of drawings in which—

Fig. 1 is a sectional elevation of a device embodying subject-matter of the invention.

Fig. 2 is a transverse section of the device shown in Fig. 1, the section being taken on line 2—2 of Fig. 1 in the direction of the arrows, and

Fig. 3 illustrates a front view of the arrangement.

The reference character 1 designates the shaft of the eccentric press, on which is mounted freely rotatable a flywheel 2, the boss 3 of the latter being provided with longitudinal recesses 4 (for example three recesses) at the left hand side face. A clutch-sleeve 5 is keyed to the shaft 1 and it is provided with longitudinally extending holes, in which pins 6 are slidably arranged. A compression-spring 7 is located in a recess, partly extending through each said pin, each said spring having the tendency to continuously force the associated pin against the flywheel of the press to enter one of the recesses 4. One end of each spring 7 rests against the bottom of the hole in the pin 6, while the other end of each said spring is engaged by the end of a bolt 9, which is slidably mounted in the recess of the corresponding pin 6. The left-hand end of each bolt 9 abuts the fixed frame of the press. The coupling just described is intended for permitting a rotation of the flywheel with respect to the sleeve in the direction of the arrow P_1 in Fig. 2, the said rotation corresponding to the transmission of power. In order to prevent any shock from being transmitted to the sleeve 5 because of the reaction of the tensed standard, an additional friction coupling is provided. This is immediately effective when because of the delivery of energy from the tensed standard, the sleeve 5 is urged to advance with respect to the flywheel, which would tend to produce a relative reverse movement between said sleeve 5 and said flywheel 2.

A sleeve 11 is provided at the outside thereof with a quick screw-thread and at the inside with a flat screw-thread of small pitch. This sleeve 11 is screwed on the reduced end 10 of the eccentric shaft 1, the said end being furnished with a corresponding flat screw-thread, and an outer sleeve 12 provided with a quick screw-thread engages with the quick screw-thread of the inner sleeve 11. The outer sleeve 12 is provided with an annular and conically shaped friction-surface 13, which is adapted to co-operate with a correspondingly shaped conical surface located at one side of the boss 3 of the flywheel. A screw-threaded pin 14 is screwed into the outer face of the sleeve 12, and one end of a tension spring 15 is hooked into the projecting end of the pin

14, while the other end of this spring engages the end of a pin 16, screwed into the end 10 of the shaft 1. The pin-coupling arranged at the left side of the flywheel, 5 serves to couple sleeve 5 and flywheel 2 to cause them to move in the proper direction (indicated by the arrow P_1 in Fig. 2), to transmit the power for the working stroke of the press. During the upstroke of the 10 ram or platen, the reaction of the standard imparts to the shaft of the press and thus also to the sleeve 11, firmly connected with the same, a tendency to advance with respect to the flywheel (equivalent to the relative 15 rotation between the flywheel and the sleeve 5, as indicated by the arrow P_2 in Fig. 2). That is, the pins 6 would tend to move towards the other ends of slots or recesses 4. Then the outer sleeve 12, which 20 is continuously urged towards the flywheel by the tension of the spring 15, is coupled to the said flywheel by the action of the conically shaped friction-face 13, and a frictional 25 clamping connection will be immediately produced between the flywheel and the shaft of the press by the action of the quick right-handed threads of members 11 and 12. The greatest part of the potential energy accumulated in the tensed standard is returned 30 to the flywheel by the friction coupling according to the present invention.

I claim—

1. A driving mechanism for presses comprising a shaft having a flywheel mounted thereon and revoluble with respect thereto, a sleeve keyed to said shaft and revoluble therewith, coupling means intermediate said flywheel and said sleeve adapted to permit the said flywheel and said sleeve to have 35 relative movements in opposite directions, said shaft having an end projecting through 40

the said flywheel, a sleeve mounted upon said projecting end of the shaft and having an external thread, an internally threaded friction drive member mounted upon said externally threaded sleeve, spring means connected to said friction drive member and to the shaft and adapted to urge the friction drive member into frictional contact with the said flywheel, the direction of the external thread of said sleeve being adapted to urge said friction drive member towards said flywheel when the said shaft is turned with respect to the flywheel to advance the coupling means from their operative positions. 50

2. A driving mechanism for presses comprising a shaft, a flywheel mounted on said shaft and revoluble with respect thereto, coupling means adapted to couple the said flywheel to the said shaft while permitting a relative movement between the said shaft and said flywheel in opposite directions, and additional coupling means between said flywheel and said shaft automatically operable 55 by a relative turning of said shaft with respect to said flywheel in the normal direction of movement of the said shaft.

3. In a driving mechanism for presses, the combination of a shaft, a flywheel 70 mounted on said shaft and freely revoluble with respect thereto, a sleeve keyed to said shaft and adapted to turn therewith, said flywheel and said sleeve respectively having interfitting pins and recesses adapted to 75 couple them, said pins being circumferentially movable in said recesses, and additional coupling means operative to couple the said shaft and the said flywheel when the said pins move in the said recesses away 80 from their normal operative positions.

LEOPOLD SCHULL.
